LID SUPPORT

Jay W. Joseph, Winston-Salem, N. C., assignor to
 Western Electric Company, Incorporated, New
 York, N. Y., a corporation of New York

Application September 16, 1948, Serial No. 49,604

8 Claims. (Cl. 217—60)

1

This invention relates to lid or cover supports and more particularly to supports for hinged or pivoted lids of cabinets or receptacles.

It is an object of this invention to provide a lid support which is relatively simple and inexpensive in construction and efficient in operation.

Another object of the present invention is to provide a lid support with an automatic latch that positively holds a lid in an elevated position without the danger of the lid falling and injuring an operator who might have a portion of his body beneath the lid.

A still further object is to provide a lid support whereby a hinged lid to an enclosure may be raised with one hand by an operator and automatically latched and held in the elevated or open position.

In accordance with one embodiment of the present invention, a strut having an elongated longitudinal slot therein is pivotally secured to a lid or cover of a cabinet. This slot is so shaped that the lower portion is enlarged and the contour of the enlarged portion is such that two cam surfaces or abutments are formed which project into the enlarged portion of the slot. To the body of the cabinet a toothed rotor is rotatably mounted so as to ride within the elongated slot. Thus when the lid is raised to a maximum position, the rotor strikes one of the cam surfaces and is rotated to a predetermined position, then when the lid is released, the other cam engages a pair of teeth on the rotor to hold the rotor stationary and the lid is latched in an elevated open position.

Other features and advantages of the invention will become apparent from the following detailed description taken in conjunction with the accompanying drawings in which:

Fig. 1 is a fragmentary side elevational view of a cabinet and lid embodying the features of this invention;

Fig. 2 is a fragmentary front elevational view of the cabinet shown in Fig. 1;

Figs. 3, 4, 5 and 6 are enlarged detailed views of the rotor and the strut shown in Fig. 1 when the lid of the cabinet is in various positions;

Fig. 7 is an enlarged detailed cross sectional view taken on line 7—7 of Fig. 1 showing the rotor, bracket and rotor support.

Referring now to the drawings wherein like 50 Fig. 1 then the rotor 21 is positioned so that the

2

reference numerals designate the same elements throughout the several views, attention is first directed to Figs. 1 and 2 wherein the reference numeral 10 designates a cabinet to which a lid 11 is pivotally supported or hinged at 12. To the lid 11 a strut or arm 13 is pivotally mounted by means of a screw 14 or any other suitable pivot member. Running longitudinally of the strut 13 is an elongated guide slot 15 having an enlarged open portion 16 at the lower end thereof. The strut is so shaped as to form two cam surfaces or abutments 17 and 18 which project into the enlarged opening 16 of the slot 15.

Secured to the cabinet 10 by any suitable means is a block 19 having an aperture therethrough for a bolt 20. A four-toothed rotor 21 is rotatably mounted on the block 19 by means of the bolt 20 and a nut 22 (Fig. 7) and it is positioned to ride within the guide slot 15. A guide bracket 23 is also rotatably mounted on the block 19 by means of the bolt 20 and the nut 22. This bracket 23 has two inturned edges 25 and 26 which form a pair of guide channels in which the strut 13 is positioned for sliding movement. In order to maintain a frictional drag on the rotor and on the bracket, a spring washer 27 is mounted on the bolt 20 between the bracket 23 and the rotor 21. The drag applied by the resilient spring washer 27 may be varied by adjusting the tension of the nut 22 on the bolt 20. Thus when a sufficient drag is placed upon the rotor by means of the spring washer 27, the rotor does not rotate nor move from a preset position unless a force capable of overcoming the frictional drag is applied to the rotor.

The shape of the rotor 21 is approximately that of a parallelogram with the opposite ends thereof notched out to provide four teeth 28, 29, 30 and 31 which form two V-shaped notches 32 and 33 (Figs. 3-6). One pair of teeth 28 and 29 positioned diametrically opposite each other is longer than the other pair of teeth 30 and 31. The V-shaped notches 32 and 33 formed by the teeth are adapted to be engaged by the abutments 17 and 18 to rotate the rotor 21 to predetermined positions when the lid is raised and lowered.

The strut support and assembled latch mechanism operates in the following manner. Assuming the lid 11 is in an open position as shown in

teeth 29 and 31 engage the abutment 18 to hold the rotor stationary and hence the lid in the elevated open position. In order to close the lid 11 of the cabinet 10, it is necessary for the operator to raise the lid to its maximum elevation whereupon the rotor tooth 30 strikes the abutment 17 and the rotor is rotated to the position shown in Fig. 3. The lid is then lowered by the operator and the strut 13 moves downward in guide bracket 23 bringing the abutment 18 into engagement with the left side of the rotor 21 whereupon continued downward movement of the strut causes the rotor 21 and the bracket 23 to rotate in a counterclockwise direction as illustrated by the solid line figure in Fig. 4. The rotation of the rotor continues until the side face of the rotor 21 is parallel with the face of the slot 13 as shown in dotted lines in Fig. 4 and thus during the remainder of the downward movement of the strut and lid, the rotor will ride within the slot 15 as indicated in Fig. 5.

When the lid is to be raised to the open position, the operator raises the lid as far as it will go. The rotor 21 rides in the slot 15 until the tooth 29 strikes the abutment 17 of the strut 13 whereupon the rotor 21 is slightly rotated to a predetermined position as shown in Fig. 6. The operator then releases the lid whereupon the notch 32 of the rotor 21 is engaged by the abutment 18 of the strut 13 to hold the rotor stationary and thus the lid is latched in an elevated open position.

It is to be understood that the above described arrangements are simply illustrative of the application of the principles of the invention. Numerous other arrangements and applications may be readily devised by those skilled in the art which will embody the principles of the invention and will fall within the spirit and scope thereof.

What is claimed is:

1. In a device for supporting a cover of a container, an arm pivotally secured to the cover and having a longitudinal slot therein, means pivotally mounted to the container for guiding said arm, a rotor rotatably secured to the container and positioned within said slot, means at one end of the slot forming a right angle abutment projecting into the slot to contact and rotate the rotor to a predetermined position when the cover is lifted, and means spaced from said first mentioned means and forming a right angle abutment projecting into the slot to engage the rotor in the predetermined position when the cover is released to hold the rotor stationary whereby the cover is held in the lifted position.

2. In a latching device for holding a pivotally mounted cover of a container in an elevated position, an arm pivotally secured to the cover and having an elongated slot terminating at its lower end in an enlarged opening, means pivotally mounted to the container for guiding said arm, a rotor rotatably mounted on said container and positioned within said slot, means to contact and rotate said rotor to a predetermined position in the enlarged opening of the slot when the cover is lifted, and means projecting into the slot to engage the rotor in said predetermined position to cause the cover to be latched in an elevated position.

3. In a device for supporting a lid of a cabinet, an arm pivotally secured to the lid, said arm having an elongated slot therein, a bracket pivotally mounted to the cabinet for guiding said arm, a rotor rotatably mounted on the cabinet and positioned within the slot, means projecting

5 into the slot to contact and rotate the rotor to a predetermined position when the lid is raised, and a second means projecting into the slot for engaging the rotor in the predetermined position when the lid is released to retain the lid in an elevated position.

4. A supporting device for hinged lids of receptacles, including an arm having an elongated longitudinal slot therein, said arm being pivotally secured to the lid, a guide member for said arm, said guide member being pivotally mounted to the receptacle, a toothed rotor rotatably mounted on the receptacle and positioned within said slot, means projecting into an enlarged portion of the slot to contact and rotate the rotor to a predetermined position when the lid is raised to a maximum elevation, and a second means forming a right abutment projecting into the enlarged portion of the slot for the purpose of engaging the teeth of the rotor in the predetermined position and to hold the rotor stationary whereby the lid is held in the elevated position.

5. In a device for supporting a lid of a cabinet, an arm pivotally secured to the lid having an elongated slot therein, the slot being enlarged near its lower terminus, the enlarged portion of the slot being of such shape as to form two opposed abutments on the arm projecting into the slot, a guide member for said arm, said guide member being pivotally mounted to the cabinet, a toothed rotor rotatably mounted on the cabinet and positioned to operate within the slot, one of said abutments being provided for the purpose of contacting and rotating the rotor to a predetermined position when the lid is lifted, and the second abutment being provided for the purpose of engaging the teeth of the rotor in the predetermined position whereby the rotor is held stationary and the lid is held in an elevated position.

6. In a device for supporting a lid of a cabinet, an arm pivotally secured to the lid and having a longitudinal slot therein, a bracket pivotally secured to the cabinet for guiding said arm, a rotor rotatably secured to the cabinet and positioned within the slot, said rotor having a plurality of notches, means projecting into the slot to contact and rotate the rotor to a predetermined position when the lid is raised, and means projecting into the slot to engage the rotor in one of the said notches when said rotor is in said predetermined position whereby the rotor is held stationary and the lid is held in the raised position.

7. In a device for supporting a lid of a cabinet, an arm pivotally secured to the lid having an elongated longitudinal slot therein, said slot being enlarged near its lower terminus to form two abutments projecting into the slot, a bracket pivotally secured to the cabinet and for guiding said arm, a rotor pivotally secured to the cabinet and positioned within the slot, said rotor having a plurality of notches, one of said abutments being provided for the purpose of rotating the rotor to a predetermined position when the lid is raised, and the second abutment being provided for the purpose of engaging one of the notches to hold the rotor stationary and to maintain the lid in the raised position.

8. In a device for supporting a pivotally mounted lid of a cabinet in an elevated position, an arm pivotally mounted to the lid and having an elongated longitudinal slot therein, the slot being enlarged at its lower terminus to form two abutments projecting into the slot, a bracket

pivotedly mounted on the cabinet and for guiding said arm, and a rotor pivotedly mounted on the cabinet and positioned within the slot, said rotor being in the shape of a parallelogram with its two ends notched, said abutments being provided for the purpose of rotating the rotor into a position so that the parallel sides of the rotor ride upon the side walls of the slot to act as a second guide means for the arm.
